(57) **CLAIM**

I claim the ornamental design for a multipurpose cutting tool, as shown and described.

DESCRIPTION

FIG. 1 is a perspective view of a multipurpose cutting tool according to my new design, shown in a closed configuration; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereto; and, FIG. 8 is another perspective view thereof, shown in an exploded configuration. The broken lines immediately adjacent and bordering shaded areas represent bounds of the claimed design while all other broken lines are for illustrative purposes only. The broken lines form no part of the claimed design.
